(57) **CLAIM**

The ornamental design for a lighting fixture, as shown and described.

DESCRIPTION

FIG. 1 is a left perspective view of a lighting fixture according to the new design;

FIG. 2 is a right perspective view thereof;

FIG. 3 is a front elevational view thereof;

FIG. 4 is a left side elevational view thereof;

FIG. 5 is a right side elevational view thereof;

FIG. 6 is a top view thereof;

FIG. 7 is a bottom view thereof;

FIG. 8 is another left perspective view of the lighting fixture;

FIG. 9 is a right perspective view thereof;

FIG. 10 is a front elevational view thereof;

FIG. 11 is a left side elevational view thereof;

FIG. 12 is a right side elevational view thereof;

FIG. 13 is a top view thereof;

FIG. 14 is a bottom view thereof;

FIG. 15 is a front perspective view of the lighting fixture;

FIG. 16 is a rear perspective view thereof;

FIG. 17 is a front elevational view thereof;

FIG. 18 is a left side elevational view thereof;

FIG. 19 is a right side elevational view thereof;

FIG. 20 is a rear view thereof; and,

FIG. 21 is a bottom view thereof.

The broken lines in the figures illustrate portions of the lighting fixture, which forms no part of the claimed design.

1 Claim, 18 Drawing Sheets
